UNITED STATES PATENT OFFICE.

RICHARD WALTON TULLY, OF SIERRA MADRE, CALIFORNIA.

STAGE APPARATUS.

1,281,718.

Specification of Letters Patent. Patented Oct. 15, 1918.

Application filed February 6, 1918. Serial No. 215,571.

To all whom it may concern:

Be it known that I, RICHARD WALTON TULLY, a citizen of the United States, and a resident of Sierra Madre, in the county 5 of Los Angeles and State of California, have invented a new and Improved Stage Apparatus, of which the following is a full, clear, and exact description.

The object of the invention is to provide 10 a new and improved stage apparatus more especially designed for changing the positions of two persons so that one disappears and the other occupies the position of the first person. Another object is to permit 15 of making the change pass without detection by the audience thus enabling an actor to play two roles in the same play.

In order to produce the desired result, 20 use is made of a set piece having an opening and a changing device extending in the said opening and having a front support adapted to support a person in view of the audience and having a rear support adapted to support and conceal another person in 25 the rear of the said set piece and out of view of the audience, the said front and rear supports being movable one relative to the other to allow the first person to disappear and the second person to occupy the place 30 previously occupied by the first person.

A practical embodiment of the invention is represented in the accompanying drawings forming a part of this specification, in which similar characters of reference indicate corresponding parts in all the views. 35

Figure 1 is a cross section of the stage apparatus with the parts in one position, the section being on the line 1—1 of Fig. 3;

Fig. 2 is a similar view of the same with 40 the parts in another position; and

Fig. 3 is a reduced sectional plan view of the stage apparatus and its setting.

The stage 10 is provided with the usual 45 footlights 11 and during the play is open at the front, and on the stage are mounted a back set piece 12 and side set pieces 13, only one of which is shown, to form a room containing, say, a mantelpiece 14, piano 15, and a small table 16 supporting a dimly 50 lighted lamp 17, as indicated in Fig. 3, but it is expressly understood that I do not limit myself to the pieces of furniture or the particular arrangement of the set pieces, as the same may be varied without deviating 55 from my invention.

As shown in Fig. 3, the set piece 13 is provided with a door 18 adjacent the table 16, and in the back of the set piece 12 is formed an opening 19 into which fits the back 20 of the frame 21 of a lounge, sofa 60 or similar piece of furniture projecting forwardly into the room, as indicated in the drawings. This piece of furniture is provided with a support 22 for a person to lie on, and its forward edge is connected by 65 hinges 23 to the front 24 of the frame 21. The back 20 of the frame 21 is provided with an opening 25 in which extends a panel 26 representing the back of the support 22. This panel 26 is mounted to swing downward 70 and forward by the use of pivots 27 connecting the lower end of the panel with the back 20 of the frame 21. From the lower end of the panel 26 extends rearwardly a second support 30 adapted to support 75 a second person. The under side of the support 30 is provided with handles 31 adapted to be taken hold of by the operator to swing the support 30 upward and forward so that the panel 26 swings downward 80 and forward to occupy the place previously occupied by the support 22, which latter at this time has swung downward into discharging position, as indicated in Fig. 2. In order to move the support 22 in unison 85 with the support 30 use is made of chains, ropes or similar flexible connections 40 each attached at one end at 41 to the support 30 and secured at its other end to a bracket 42 fastened to the under side of the support 22 90 at the free end thereof. Each flexible connection 40 extends upward and passes over a pulley 43 journaled on the back 20 of the frame 21. A flexible strip 50 of cloth or a similar material is attached to the top of 95 the back 20 and depends from the rear thereof in the back of the panel 26, and this strip serves to cover the upper portion of the opening 25 during the time the back 26 swings downward and forward while the support 30 swings upward and forward into the position previously occupied by the panel 26.

Normally the parts are in the position shown in Figs. 1 and 3 and a person is resting 105 on the support 22 in full view of the audience while another person is resting on the support 30 out of view of the audience. When it is desired to change the persons, the operator takes hold of the handles 31 110

and swings the support 30 thus allowing the support 22 to swing downward whereby the person on the support 22 rolls down the same to the rear while the other person rolls 5 over onto the downwardly moving panel 26 to be completely supported thereon as soon as this support 26 reaches the position previously occupied by the support 22, as plainly shown in Fig. 2. When the back 26 moves 10 into supporting position its free end rests on the end of the support 22 thus holding the back 26 in an approximately horizontal supporting position while the brackets 42 of the support 22 rest on the floor. It will 15 be noticed that during this movement the support 30 becomes the back panel for the frame 21.

The stage apparatus shown and described is of special service when it is desired that 20 an actor play two rôles in the same play, as, for instance, in "The Masquerader," a play by John Hunter Booth, one actor plays the rôles of both Loder and Chilcote, M. P. Thus while a dummy of Chilcote is resting 25 on the support 22 in a supposed stupor the actor representing Loder is in the room, and when it is desired that Loder should take the place of the dummy then Loder passes out of the room through the door 18 to the 30 rear of the set piece 12 and, after a quick change of dress, lies down on the support 30, after which the operator makes the change as above described so that the dummy passes out of sight and Loder now in the rôle of 35 Chilcote appears lying on the support 26 within the room to act the tragic end of Chilcote.

Having thus described my invention, I claim as new and desire to secure by Letters 40 Patent:

1. A stage apparatus, comprising a set piece having an opening and a changing device extending in the said opening and having a front support adapted to support a 45 person in view of the audience, and having a rear support adapted to support and conceal another person in the rear of the said set piece, the said front and rear supports being movable one relative to the other to 50 allow the first person to disappear and the second person to occupy the place previously occupied by the first person.

2. In a stage apparatus, a swinging support adapted to support a person in view of 55 the audience, and a turning support adapted to support and conceal a second person, the said swinging support being adapted to move out of supporting position and relieve itself of its person out of view of the audience, and the said turning support being adapted to move simultaneously and display its person to the audience in lieu of and in 60 the place formerly occupied by the said first person.

65 3. A stage apparatus, comprising a set

piece having an opening therein and a lounge having its back frame fitting the said opening, the said lounge having a hinged main support adapted to support a person, the said lounge having a back panel provided with a rearwardly extending auxiliary support adapted to support a second person, the said back panel being adapted to swing downward and forward to occupy the place of the said main support, and the said auxiliary support being adapted to form the back panel of the lounge.

4. A stage apparatus in the form of a sofa, comprising a frame, a main support hinged to the frame and adapted to swing downward, a back panel mounted to swing on the frame and adapted to occupy the place of the said main support, and an auxiliary support extending rearwardly on the said back panel and adapted to occupy 85 the place of the back panel on the latter occupying the place of the said main support.

5. A stage apparatus in the form of a sofa, comprising a frame, a main support 90 hinged to the frame and adapted to swing downward, a back panel mounted to swing on the frame and adapted to occupy the place of the said main support, an auxiliary support extending rearwardly on the 95 said back panel and adapted to occupy the place of the back panel on the latter occupying the place of the said main support, and means connecting the said main support with the said auxiliary support to move the 100 main support and the said back panel and its auxiliary support in unison.

6. A stage apparatus, comprising a lounge frame, a support hinged at its forward end to the front of the frame to swing downwardly into an inclined discharging position, a back panel pivoted at its lower end on the said frame and adapted to swing downward and forward to occupy the place of the said support at the time the latter swings into discharging position, and a second support extending rearwardly from the lower end of the said back panel and adapted to swing upward and forward to occupy the place of the said back panel at the time the latter occupies the place of the said first-named support.

7. A stage apparatus, comprising a lounge frame, a support hinged at its forward end to the front of the frame to swing downwardly into an inclined discharging position, a back panel pivoted at its lower end on the said frame and adapted to swing downward and forward to occupy the place of the said support at the time the latter swings into discharging position, a second support extending rearwardly from the lower end of the said back frame and adapted to swing upward and forward to occupy 125 the place of the said back panel at the time 130

the latter occupies the place of the said first-named support, a pulley journaled on the said frame, and a flexible connection between the said supports and passing over 5 the said pulley.

8. A stage apparatus, comprising a lounge frame, a support hinged at its forward end to the front of the frame to swing downwardly into an inclined discharging position, a back panel pivoted at its lower end on the said frame and adapted to swing downward and forward to occupy the place of the said support at the time the latter swings into discharging position, a second 10 support extending rearwardly from the lower end of the said back panel and adapted to swing upward and forward to occupy the place of the said back panel at the time the latter occupies the place of the said first- 15 named support, and handles on the under side of the said support.

9. A stage apparatus, comprising a lounge frame, a support hinged at its forward end to the front of the frame to swing downwardly into an inclined discharging position, a back panel pivoted at its lower end on the said frame and adapted to swing downward and forward to occupy the place of the said support at the time the latter swings into discharging position, a second 20 support extending rearwardly from the lower end of the said back panel and adapted to swing upward and forward to occupy the place of the said back panel at the time the latter occupies the place of the said first- 25 named support, and a flexible strip depending from the top of the frame at the rear thereof and the rear upper portion of the said back panel to cover the opening on the back panel swinging downward and forward. 30 35 40
